ATTY 5.

UNITED STATES PATENT OFFICE.

ALEXANDER LAWRENCE CURRIE, OF SOREL, QUEBEC, CANADA.

TRACK-SIGNAL.

1,361,308.

Specification of Letters Patent.

Patented Dec. 7, 1920.

Application filed October 10, 1919. Serial No. 329,813.

To all whom it may concern:

Be it known that I, ALEXANDER LAWRENCE CURRIE, a subject of the King of Great Britain, and resident of the village of Sorel, in the Province of Quebec, Dominion of Canada, have invented certain new and useful Improvements in Track-Signals, of which the following is a specification.

This invention relates to improvements in track signals of the type adapted to be removably adjustable relatively to the track by working gangs or other parties who are temporarily using the tracks or for yard purposes, or under any circumstances in which manual flagging is at present employed, and the objects of the invention are to improve and simplify the construction of the signal and to adapt the various parts to better perform the functions required of them.

With the above and other objects in view, the invention consists essentially of the improved construction hereinafter described in detail in the accompanying specification and drawings.

In the drawings:

Figure 1 is a front elevation of an embodiment of my invention.

Fig. 2 is a fragmentary enlarged elevation of the base member and flag supporting arm.

Fig. 3 is a plan view of the rod engaging and supporting the flag.

Fig. 4 is a fragmentary front elevation of the clamping member for engaging the flange of the rail.

Fig. 5 is a fragmentary front elevation of an alternative cam clamping means whereby the base member is secured to the lower flange of the rail.

Fig. 6 is a fragmentary front elevation of an alternative form of cam clamping member for securing the base to the flange of the rail.

Fig. 7 is a fragmentary front elevation of another alternative means for securing the signal to the rail.

Like characters of reference refer to the like parts in the several figures.

In the drawings, A represents a rail of a track and B the improved signal attached thereto.

This signal comprises a base member 10 having a flattened end 11 formed with a hook gripping member 12, and the flattened portion of the base 10 is designed to underlie the rail A, so that the hook gripping

member will engage with the lower flange of the said rail.

The opposite end 13 of the base member 10 is offset and tubular and provided with a Z-shaped slot 14. The base member 10 is secured in position by means of a clamping plate 15, and a ring 16 embraces the plate 15 and flattened portion 11 of the base 10, so that the plate 15 may be tightened into engagement with one of the lower flanges of the rail A by means of a set screw 17.

The ends of the plate 15 are offset in opposite directions, one end to engage with the flange of the rail A, and the other end to hold the plate 15 in spaced relation from the flattened portion 11 of the base 10, so that as the set screw 17 is tightened it will force the plate 15 against the flange of the rail to hold the base member 10 in position.

The rod 18 has a pin 19, on its lower end which slidably engages with the Z-shaped slot 14, so that as the rod 18 is pushed into the offset tubular end 13 of the base member 10, the pin will slide down the slot until it reaches the bottom thereof, but it should be particularly noticed that the rod 18 is given a slight turn, when the pin 19 reaches the center of the slot, so that the said pin may be brought into alignment with the lower arm of the Z-shaped slot. It will be evident that the rod 19 cannot become disengaged from the tubular end 13 of the base member 10 unless the said rod is manually and intentionally removed.

The upper end 20 of the rod 18 is flattened forming a shoulder, and an elongated eyelet 21 formed on one end of the rod 22 engages with the flattened end 20 of the rod 18 and rests against the said shoulder, the other end of the rod 22 being offset.

This rod 22 carries the flag 23 hung therefrom, which is prevented from becoming disengaged by the offset end on the rod, and the lower end 24 of the flag may be weighted so that it will hang in proper position but will not prevent the flag from fluttering, and the flag may be rendered visible at night time by hanging a lamp from the upper end 20 of the rod 18.

This type of a signal can be very easily set up and secured in position and will not work loose through jarring or from any other cause.

The clamping member shown in Fig. 4, is an alternative to that shown in Fig. 1, in that, the set screw 17 is threaded through

the outer end of the plate 15, and the ring 16 is used in this type, and, as the set screw 17^a is tightened, it will lift the outer end of the plate 15 and force the inner end hard 5 against the flange of the rail A.

In Figs. 5 and 6 the set screw is dispensed with, and in Fig. 6 the ring 16 is provided with a cam member 25 formed with a hand grip which may be actuated to force the 10 plate against the flattened portion 11 of the base member 10 and against the lower flange of the rail A.

Fig. 6 differs from Fig. 5 with respect to the location of the cam 25^a which is positioned in the end of the plate 15^a. When the 15 cam 25^a is used, the plate 15^a has its outer offset end removed but the inner offset end coacts with the lower flange of the rail A, and the ring 16 is used so that on actuation 20 of the cam 25^a the plate 15^a will be forced hard against the lower flange of the rail A to secure the signal in position.

In Fig. 7 the rod is provided with a laterally turned lower end 2 adapted to extend 25 across the top of the rail and formed with a downwardly turned projection 3 adapted to engage the side of the head of the rail A.

4 represents a projection depending from

the offset end 2 of the rod 1 and extending to the opposite side of the rail head to the 30 end 2, and adapted to receive a screw threaded crank 5, the end of which is adapted to bind against the side of the rail A.

As many changes could be made in the above construction and many widely different embodiments of my invention within the scope of the claim, constructed without departing from the spirit or scope thereof, it is intended that all matter contained in the accompanying specification and drawings 35 shall be interpreted as illustrative and not in a limiting sense.

What I claim as my invention is:

A track signal, comprising a base member having a clamping means for securing same 40 to a rail and provided with an offset end, a flag carrying member engaging with the offset end and provided with an upper offset end, a rod having an eyelet engaging with the offset end of the last said rod, a flag 45 mounted in the second rod and means for weighting the lower end of the flag to hold it in position but not impair its fluttering.

In witness whereof I have hereunto set my hand.

ALEXANDER LAWRENCE CURRIE.
